UNITED STATES PATENT OFFICE.

ANDREW J. SHEPARD, OF BUFFALO, NEW YORK.

NUT-MACHINE.

Specification of Letters Patent No. 26,446, dated December 13, 1859.

To all whom it may concern:

Be it known that I, ANDREW J. SHEPARD, of the city of Buffalo, county of Erie, State of New York, have invented certain new 5 and useful Improvements in Nut Machines; and I do hereby declare that the following is a full, clear, and exact description of the construction and operation of the same, reference being had to the annexed drawings, 10 making a part of this specification, in which—

Figure I, is a front elevation of my improved machine. Fig. II, is a longitudinal section of the same taken at right angles to 15 the front elevation and passing through the center lines of the punches and nut box. Fig. III, is an elevation of machinery for forming hexagon nuts. Fig. IV, is a plan of nut box. Fig. V, is a modified and preferred form of nut box. Fig. VI, is an end elevation of the stationary part of the nut box with the cutter attached. Fig. VII, is an end elevation of the movable part of the 20 nut box with cutter attached. Fig. VIII, is a longitudinal section of the round punch showing its connection with its stock and water pipe. Fig. IX, is a longitudinal section of the angular punch showing also its connection with its stock and water pipe.

30 Characters of like name and kind refer to like parts in each of the figures.

The frame of the machine consists of two upright parts (A) upon which journal boxes (A') are supported. The bottoms of the upright parts (A) rest upon journal boxes (A²) similar to (A'). These journal boxes in turn rest upon the bed plates (A³). The whole is held together by the tension bars (A⁴). The journal boxes (A') are connected together by the crosshead (B) and the journal boxes (A²) by the crosshead (B'). These crossheads act as guides to the punch stock or pistons C and C' which move in apertures through them. To the lower 40 punch stock (C') an angular punch or cutter (D') is attached of the size and shape of the nut to be made, whether the same be square hexagon or octagon in form. A cylindrical hole is made extending through the whole length of this angular punch (D') and punch stocks C' into which a movable punch, f, of the same size as the punch, e, or of the hole to be made in the nut blank is placed. A spiral spring (g) is coiled around the punch one end pressing against a shoulder in the punch stock (C') and the

other resting on a shoulder on said punch as shown in Figs. I and II. The object of this punch is hereinafter more fully set forth. It may be dispensed with altogether 60 in which case the angular punch is made as shown in Fig. IX as hereinafter described. A round punch e is secured to the upper punch stock (C). It is made of the proper size to punch the hole in the nut blank. 65 These punches are worked by cams—the upper punch and punch stock being operated by the cam (H) upon the shaft G. This shaft turns in the journal boxes (A') and has a spur wheel I, on one end. The lower 70 angular punch D' and round punch f are operated by the cams (H') and (H²) on shaft (J) which also has a spur wheel (K) on one end. In case the round punch f is dispensed with the cam (H²) is also dispensed with, but the motion of the other cams remain the same. 75

At the proper point between the upper and lower punches I place a nut box (L, M). It is made in two parts as shown in Figs. 80 IV and V, Fig. V, showing it on a larger scale and in a more perfect and practical form.

In the operation of the machine the part, L, is stationary and secured to the frame 85 (A) though it may be removed and changed according to the size and shape of the nut to be made. The part, M, is movable and slides in grooves in the frame (A). It is operated by the cam, N, on the shaft, P, 90 turning in journal boxes on an extension, O, of the frame, (A). A spur wheel Q on one end of the shaft, P, gears with spur wheel (I) on shaft (G). The contiguous ends of 95 the two parts of the nut box, are so formed that they will leave an opening, either square, hexagon, or octagon, in shape; according to the required shape and size of the nut to be made. The drawing represents the opening as square, the diagonal of the 10 square being on the longitudinal center line of the nut box. A rectangular aperture large enough to admit the bar of iron from 10 which the nuts are to be made, is formed in the part L perpendicular to one of the sides of the opening, as shown by the dotted lines (2 and 3). Directly over this aperture is placed a steel cutter (t) the outer face of which is parallel to, and forms part of, the side of the opening as shown in Fig. VI. 11 In the part, M, directly opposite to the cutter (t) a second steel cutter (t') is placed.

Below it the side of the opening is cut away so as to allow it to project from the surface of the side of the opening and form a cutting edge which will cut off the rag-end of the bar. Motion being given to the driving wheel (R) it is communicated to the spur wheels, turning the several cams which operate the punches and nut box by the pinion (S) which gears with the spur wheels (K and Q) the spur wheel (Q) as before stated gearing with spur wheel I. The bar is now fed to the punches, the motions of the various parts being so regulated that the cam (N) will first move the part M of the nut box until it comes in contact with the part, (L) when the angular punch (D') and central punch *f* by means of cams H' and H² commence their upward movement. But before the punch D' rises high enough to come in contact with the bar which passes through the part (L) into the opening formed by the nut box the part M will have completed its movement. By thus timing the movements, should the bar be fed in too far, the part M will bring it back to its proper place, when the upward motion of the angular punch, causes it, in connection with the steel cutter (*t*) to cut off the nut blank from the bar. At about the same time the angular punch (D) commences its upward movement the cam (H) causes the punch *e* to commence its descent. After the nut blank is cut from the bar the round punch *e* will come in contact with the said nut blank and at the same time the cam H² will have raised the punch (*f*) until it will be in contact with the nut blank directly under the punch *e*. Their motion being continued they will displace the amount of metal necessary to form the hole in the nut and force it into the body of the nut, and will meet each other (or nearly so) near the center of the nut. At this movement the cam (H²) will cease to act upon the punch *f* and the spring (*g*) will cause said punch to drop down until its end comes as low as the holes (*u*) in the punch stock (C'). The cam (H) will still cause the punch (*e*) to descend until it has passed entirely through the nut punching out whatever metal there may have been left between the punches, and allowing it to drop out through the holes (*u*). The cam (H) will then cease to act upon the punch stock (C) and the spring (V) will withdraw the punch (*e*) from the nut and raise punch stock and punch as high as may be desired. At the same time the cam (H') will cease to act upon the punch stock (C') and the spring (V') will cause the said stock to descend as much as may be necessary. At nearly the same time the cam (N) will cease to act upon the part (M) and the springs (V²) will cause it to move back, as far as may be necessary leaving the

nut free to be removed by any proper means. During this operation the nut blank is held firmly by the nut box the angular punch (D') forming a table or bottom to resist the pressure of the punch (*e*). In case the punch (*f*) is dispensed with as in practice it most probably will be, the motions of the other parts remain precisely the same—that is as soon as the angular punch has cut off the nut blank the punch (*e*) will come in contact with the nut blank and punch the hole through it, the core dropping down through the angular punch and punch stock, the angular punch as before stated resisting the pressure of the punch (*e*) in punching the hole. In this case the core is punched out, instead of being forced into the body of the nut.

The punch (*e*) is prevented from lifting the nut when it is being withdrawn by a bar 85 of metal (4) secured to the part and covering the opening formed by the nut box, a hole being made through it, through which the punch works, but through which the nut can not pass. The punch (*e*) has an enlargement or shoulder, D, either round or angular which is countersunk to form a washer on the nut.

I prevent the punches from becoming hot, by the use of water as follows. I conduct a stream of water through the pipe (*w*) into the aperture (*x*) in the punch *e*. One or two small openings (5, 6) are made in the side of punch (*e*) as near the bottom as possible to allow this water to escape and 100 keep a constant current of water running through the punch thus keeping the punch cool. The angular punch (D') has a cylindrical chamber (*y*) which is filled with water from the pipe *z*. When the punch 105 (*f*) is used, several openings are made into the holes (*u*) to allow of the escape of the water thus keeping up a constant circulation of cool water through the punch. As the water issues into the holes (*u*) it falls 110 onto the head of the punch (*f*) after the said punch has ceased to be acted upon by the cam (H²) and has dropped down even with the said holes (*u*) and keeps it cool—or the punch may be constructed as shown 115 in Fig. IX which shows the angular punch when constructed without the central punch (*f*). In this case the water issues into the cylindrical cavity (*y*) from the pipe (*z*) from whence it flows through openings in 120 the collar (7) into chamber (8) and out through the holes (9 and 10) thus keeping up a constant circulation of cool water through the punch and keeping the punch cool. Holes are made through the cutters *t* and *t'* 125 as shown by the dotted lines (11 and 12) Figs. V, VI, and VII through which a constant stream of water will flow, being supplied from the water in the recesses *l* and *m*, in the nut box thus keeping the cutters per- 130

fectly cool. The nut box (L M) is kept cool in a similar manner—recesses *l* and *m* are made in the two parts which are kept full of water from the pipes (*o*, *p*.) which connect with the pipes (*w*). The recesses being provided with vents to keep up the circulation of cold water. In this way I prevent the cutters nut box and punches from becoming heated.

10 For making hexagon nuts I place two heavy spur wheels (*S'* and *S²*) gearing with each other on one side of the machine. Steel dies (*T'* and *T²*) are bolted to these spur wheels. These dies are so formed that 15 if the bar from which the nut is proposed to be made, be run in between these, when they are in motion they will form the bar into hexagon nut blanks connected together at opposite sides. I am thus enabled to save considerable metal and make a more solid 20 nut, than when the form is given by cutting. In this case hexagon punches and nut box

of the required size and shape should be used.

Having thus fully described my improved 25 nut machine, what I claim therein as new and desire to secure by Letters Patent is—

1. Perforating the punch (*e*) as described, for the purpose set forth.

2. The cutters *t*, and *t'*, when constructed 30 and arranged, relatively to the dies L, and M, as herein described.

3. The combination of the dies L, and M, with the water-chambers *l*, and *m*, when arranged and operating substantially as described, for the purpose set forth. 35

4. The combination and arrangement of the punch D, Fig. IX, with the water-chamber *y*, and openings 8, 9, substantially as, and for the purpose described.

ANDREW J. SHEPARD.
